UNITED STATES PATENT OFFICE

EDOUARD FRED SATZ, OF ANTWERP, BELGIUM

PROCESS AND APPARATUS FOR THE MANUFACTURE OF CARDBOARD MATCHES

Application filed May 23, 1930, Serial No. 455,099, and in Belgium May 30, 1929.

This invention relates to the manufacture of cardboard matches and it has for its object to provide a process and apparatus whereby a continuous strip or band of cardboard may be converted, in a continuous manner, into leaves of matches ready for packing into folders.

In accordance with this process, a strip of cardboard, whose width is twice that of the length of a match and its tab, is led progressively into an enclosed space where paraffin is applied along its two edges, through a machine which successively prints it and slits it to the required depth corresponding to the length of the matches to be made and is then gripped between guides inserted between match stems alternately offset on each side of the strip, whereupon the matchheads are tipped and the strip is cut into leaves after having been dried.

The apparatuses used to ensure the uninterrupted sequence of the said operations are arranged so that they may function with the utmost efficiency, whilst taking up a minimum of space.

In the attached drawings, which illustrate by way of example one form of construction of the apparatus according to this invention adapted to operate on two strips circulating side by side:

Fig. 1 is a diagrammatic general view of the apparatus in longitudinal section.

Fig. 2 is a detail view of the paraffin coating discs, the strips to be coated being shown in section.

Fig. 3 is a plan view of the printing mechanism, the cardboard strips being shown in section.

Fig. 4 is an edge view of a printing disc.

Figs. 5 and 6 are edge views of interlocking printing discs, and

Fig. 7 shows one such disc in perspective.

Fig. 8 is a perspective view of a piece of strip, partly printed and slit.

Fig. 9 is a plan view of the slitting devices.

Fig. 10 shows a frontal elevation of the offsetting devices and

Fig. 11 is a plan view of the same.

Fig. 12 shows a frontal elevation of complementary cutting devices.

Figs. 13 and 14 are a front view and a side view of the dipping devices respectively.

As shown in Fig. 1 the cardboard strips *a* proceed first through a tower 1 in which they are coated with paraffin in a heated atmosphere. Upon leaving the top of tower 1, they are guided downwards into the printing and slitting machine 2, whence they are led into a chamber 3 in which the heads are dipped and the strips are dried and thence to 4, where they are cut into leaves.

The strips *a* pass horizontally into the base of the tower 1, are led upwards by feed-rollers 5 towards guiding rollers 6, continue their course downwards between the paraffin coating discs 7 and 8 and are again guided upwards towards guiding rollers 9, emerging horizontally thereafter from the top of the tower.

The discs 7 are partly immersed in a bath 70 of melted paraffin 10 heated by a pipe 11. These discs carry outside flanges 7' (Fig. 2) fitting accurately in grooves 8' of the discs 8. The edges of the strips *a* are thus enclosed on all sides at the point where they pass between discs 7 and 8.

One side of the strip edge is coated with paraffin by the discs 7 and the other side by the discs 8 to which paraffin is fed by contact with the inner surfaces of the flanges 7'.

A driving shaft 12 actuates the discs 7 and rollers 5 through suitable connections 13.

Steam heated radiators 14 maintain the interior of the tower 1 at a suitable temperature. The tower is ventilated by a chimney 85 15 opening into the lower part thereof, all other openings being carefully sealed against any leakage of paraffin fumes.

The two strips *a* pass from the paraffin coating apparatus into the printing and slitting machine 2 which comprises an upright frame in which the shaft bearings of various mechanisms are mounted above one another.

The strips *a* enter at the top of the machine and proceed downwards whilst undergoing successive treatments and emerge horizontally at the lower end of the machine. This vertical arrangement not only reduces considerably the bulk of the machine but renders its various parts easily accessible and facil- 100

tates supervision of both sides of the strip.

All the mechanisms in this apparatus are controlled in synchronism by means of an endless screw 16 which actuates worm wheels 17 mounted on the shafts of said mechanisms (Figs. 1 and 3).

The strips first pass between a pair of driving rollers 18, then between the type rollers 19 and the smooth supporting rollers 20 of the printing mechanisms.

Each type roller consists of a plurality of discs 21 keyed upon a common shaft 22 (Fig. 3) and inked by inking rollers fed from cups 24.

Any one desired type is repeated round the whole circumference of each disc 21 (Fig. 4). When a plurality of such discs are assembled in predetermined sequence into a roller, a cylindrical block is formed, which repeats along its periphery any desired line of text.

If a two line text is required, a gap equal to the height of the type is left between the succeeding types of one disc (Fig. 5) and the width of each disc is conveniently reduced to one half of the width of the type by offsetting the latter to one or other side of its carrying disc, the result being that when two such gapped discs are coupled, the types of each interlock with the gaps of the other and a composite disc is formed, along the edge of which the two kinds of type alternate regularly.

Fig. 5 shows from left to right: left hand disc 25, right hand disc 26 and the composite interlocked disc. Such composite discs are then assembled to form a type roller.

If a three line text is required, a roller is similarly assembled of composite discs consisting of three single discs 27, 28, 29 bearing three kinds of alternating types (Fig. 6). In this case the gap left between the succeeding types of any single disc is equal to twice the height of a type and the width of the disc is reduced to one third of the width of the type. Fig. 7 shows a single disc in perspective.

The rollers 19 and 20 are preferably arranged alternately on both sides of strips *a*, so as to print on one face of each strip the text *c* placed on one side of centre line *b* of the strip and to print on the opposite face the text *c'* placed on the other side of the centre line (Fig. 8).

After the matches have been made, the cardboard need then only be folded along its centre line *b*, when the matches will take up the position which they are to take in the folders, thus saving much time.

Upon leaving the printing rollers the two strips *a* enter the slitting mechanism which cuts, on either side of tab *d* of each strip (Fig. 8), transverse slits spaced from each other by the width of one match *e* and coinciding with the gaps between successive texts *c* or *c'*.

The slitting mechanism consists of discs

30 fitted with radial cutters 31 facing smooth discs 32 (Figs. 1 and 9) which press the strips against the cutters and thus allow the same to slit the strips.

The cutter discs 30 and smooth discs (Fig. 9) are positioned alternately in a manner similar to the printing discs (Fig. 3). In penetrating the cardboard, the cutters make the surface of one side of the matchstems convex and the surface of the other side concave, so that all texts appear on the convex sides and an appearance of careful finish is imparted to the matches.

In order that the depth of the slits may be exactly adjusted the bearings 33 of the cutter bearing shafts 34 are mounted adjustably between fixed supports 35 and the distance between said bearings may be lessened as required by tightening screws 36 against the pressure of spring 37 inserted between said bearings (Fig. 9).

Since the slits must exactly coincide with the gaps between the texts, two cams 38, 39 are inserted for purposes of adjustment to bear against the portions of strips extending from the printing mechanism to the slitting device. By moving these cams at an angle, the portion of strip between them may be inclined slightly and the length of cardboard between the points at which the treatments take place may be increased or reduced according to need. Similar cams may also be inserted at other places.

The vertical position of the strips in machine 2 allows both sides of each strip to be constantly visible and all adjustments may therefore be effected with complete accuracy.

Strips *a* then pass into the offsetting mechanism, which alternately raises and depresses successive matchstems above and below the level of the strips as a preliminary to the tipping of each match head with ignitable composition in the dipping apparatus. For this purpose each row of matchstems passes between a pair of cogwheels 40 (Figs. 1 and 10) whose teeth are spaced by twice the width of a match and which press the stems out of the level of the strip. To prevent the return to the level of the strips, of the stems thus offset, triangular shaped laths 41 (Fig. 11) are provided below the offsetting mechanism to act as wedges between the successive matches *a'* and guide the strip until dipping is completed.

Upon leaving the offsetting mechanism, the two strips pass between smooth rollers 42 and cutter discs 43 (Figs. 1 and 12). The cutters 44 of discs 43 are suitably spaced to cut off one match in nine, in ten, in eleven or in any required number, according to the width of a folder.

Since the matches do not always fall by their own weight, the strip is led on into a clearing device consisting of smooth rollers 45 and of discs 46 similar to rollers 42 and

discs 43 except that, instead of carrying cutters, the discs 46 are provided with teeth to detach the cut matches.

- The synchronism of the above operations is insured by the provision, below the clearing device, of a pair of rollers 47 adapted to keep the strip taut and to exert upon the same a pressure which may be regulated by reducing or increasing the distance therebetween.
- 10 In view of subsequent packing in folders, the next operation is that of making a longitudinal groove along centre line *b* of the strip (Fig. 8) and this is effected by means of smooth rollers 48 and of circular cutters 49 (Fig. 1).

The strips emerge horizontally from the printing and slitting apparatus after passing between guiding rollers 50 and enter the dipping and drying apparatus 3 under continued guidance by the triangular laths 41.

20 The strips pass first between horizontal driving rollers 51 and at 52 they are placed on edge by a 90° turning motion.

This quarter turn is most conveniently obtained by imparting a helical twist to laths 41. The strips thus arrive above the dipping tank 53, containing the ignitable composition, in such position that the match ends along one edge of the strip point downwardly.

0 Two discs 54, partly immersed in dipping tank 53, are driven by an endless screw 55 at a peripheral speed substantially equal to that of the strips. These discs are provided at their periphery with slots 56, into each of 5 which one of the rows of match heads on either side of the lower triangular lath engages (Figs. 13 and 14).

In passing, each match is tipped with a small quantity of composition contained in 10 the corresponding slot of the disc and it is thus furnished with an ignitable head.

Strips *a*, now supplied with heads along one of their edges, are kept moving for a suitable time in a heated atmosphere constantly 15 renewed by means of a ventilator 57. When the heads have set, the strips *a* are turned through 180° at 58 so that their opposite edges are turned downwards. As in the previous instance, this turning motion is most 20 conveniently imparted by a helical twist in laths 41. The ends of the match stems of this edge are tipped in their turn with composition by grooved discs 54, partly immersed in dipping tank 53' and are then subjected 25 to a blast of hot air by ventilator 57'.

The strips are then again turned through 90° into a horizontal position, whereupon they pass between feed rollers 59 and enter the dryer 60 situated above the dipping apparatus, in which drying and hardening are completed.

In dryer 60, the strips *a* follow a zig-zag course between two series of roller pairs 61, 62 driven by a common control. Upon emerging 65 from dryer 60 the strips enter a section-

ing mechanism 4 provided with a rotary blade 63 which cuts and ejects them in sheets or leaves *a'* of suitable length.

It then only remains to fold these leaves along the central groove cut by blade 49 and 70 to pack them in folders.

It will be understood that the details of construction herein shown by way of example may be changed without departing from the scope of this invention as defined by the ap- 75 pended claims.

I claim:

1. In a process of making matches from a continuous strip of cardboard, continuously moving said strip, coating both sides thereof with paraffin along its longitudinal edges, slitting said strip transversely from both edges to a depth corresponding to the length of the matches to be made to form a succession of matchstems, alternately offsetting said matchstems on each side of said strip, inserting guides between said offset match stems along both edges of said strip, successively tipping the match stems along each edge of said strip while said strip is being guided, and cutting said strip into leaves. 80

2. In a process of making matches from a continuous strip of cardboard, moving said strip through a heated atmosphere, coating both sides of said strip with paraffin while 90 in said heated atmosphere, causing said strip to travel downwardly, successively subjecting said strip to printing and slitting operations while travelling downwardly to form a succession of printed match-stems, alternately offsetting said matchstems on both sides of said strip, tipping said match stems while keeping them offset, and cutting said strip into leaves. 95

3. In a process of making matches from a continuous strip of cardboard, continuously moving said strip, coating both sides thereof with paraffin along its longitudinal edges, simultaneously printing one face of said strip on one side of its longitudinal axis and the opposite face on the other side of said axis, forming successive matchstems by transversely slitting said strip from each edge to a predetermined distance from said longitudinal axis, alternately offsetting said matchstems on both sides of said strip, tipping said matchstems and cutting said strip into leaves. 100 110

4. In a process of making matches from a continuous strip of cardboard, causing said strip to move downwardly, simultaneously printing a succession of text lines on both faces of said strip, the lines on one face being on one side of the longitudinal axis of said strip and the lines on the opposite face on the other side of said axis, and simultaneously applying cutting edges between the text lines on both faces of said strip. 115 120

5. In a process of making matches from a continuous strip of cardboard, continuously moving said strip, coating both sides there- 125 130

- of with paraffin along its longitudinal edges, transversely slitting said strip from each edge to a predetermined distance from said longitudinal axis to form a series of matchstems on each side thereof, alternately offsetting said matchstems on both sides of said strip, successively causing each series of matchstems to point downwardly, and tipping the matchstems of each series while pointed downwardly.
6. In a process of making matches from a continuous strip of cardboard, paraffining the edges of said strip, continuously moving said strip downwardly, successively subjecting said downwardly moving strip to printing, to transverse slitting into two series of matchstems extending outwardly from the central portion of said strip, and to alternate offsetting of said matchstems, causing said strip to take up a horizontal course, twisting said strip to cause one series of matchstems to point downwardly, tipping said downwardly pointing matchstems, twisting said strip to cause the other series of matchstems to point downwardly, and tipping the matchstems of said other series.
7. In a process of making matches from a continuous strip of cardboard, continuously moving said strip, coating both sides of said strip with paraffin, transversely slitting the edge portions of said strip into two series of matchstems extending outwardly from the central portion of said strip, alternately offsetting the matchstems of both series on both sides of said strip, introducing said strip into a heated atmosphere, successively causing each series of matchstems to point downwardly, tipping the matchstems of each series while pointed downwardly, drying the tipped matchstems, moving said strip out of said heated atmosphere, and cutting said strip into leaves.
8. In apparatus for the manufacture of matches from a continuous strip of cardboard, the combination of a vertical tower, means for guiding a strip of cardboard into said tower, up and down in said tower and out of the top of said tower, means in said tower for applying paraffin on both edges of said strip, means for heating the atmosphere inside said tower, a vertical frame adjacent said tower, printing, slitting and offsetting devices arranged in superposed relation in said frame, means for guiding said strip from the top of said tower downwardly through the devices in said frame, a tipping apparatus adjacent said frame, and means for guiding said strip from the bottom of said frame through said tipping apparatus.
9. In apparatus for the manufacture of matches from a continuous strip of cardboard, the combination of a vertical tower, means for guiding a strip of cardboard into said tower, along a zigzag path vertically up and down in said tower and out of the

top of said tower, a paraffin tank at the bottom of said tower, discs revolving in said tank, said discs being adapted to engage the edges of said strip at an intermediate point of said zigzag path, and vertical radiators 70 in said tower.

10. In apparatus for the manufacture of matches from a continuous strip of cardboard, the combination of a vertical tower, means for guiding a strip of cardboard up 75 and down in said tower, a paraffin tank at the bottom of said tower, flanged discs revolving in said tank, rotatable recessed discs above said flanged discs, said flanged and recessed discs being in mutual engagement and 80 adapted to enclose the edges of said strip between them.

11. In apparatus for the manufacture of matches from a continuous strip of cardboard, the combination of a vertical frame, 85 a printing device in said frame comprising a printing roller and a plain roller adapted to engage one face of said strip, and a printing roller and a plain roller adapted to engage the opposite face of said strip, each 90 printing roller facing a plain roller, and under said printing device, a slitting device in said frame comprising slitting rollers and bearing rollers adapted to engage said strip, said slitting and bearing rollers being in 95 equal number and similarly arranged with respect to each other as said printing and plain rollers.

12. In apparatus for the manufacture of matches from a continuous strip of cardboard, 100 the combination of a vertical frame, a printing device in said frame, a slitting device in said frame below said printing device, means for guiding a strip of cardboard through said printing and slitting devices, 105 and cam means in said frame adapted to engage said strip to vary the length thereof comprised between said printing device and said slitting device.

13. In apparatus for the manufacture of 110 matches from a continuous strip of cardboard, the combination of a paraffining apparatus, a vertical frame adjacent said apparatus, means for leading a strip of cardboard from said apparatus to the top of said 115 frame and down said frame to the bottom thereof, means in said frame for printing one face of said strip on one side of its longitudinal axis and the opposite face on the other side of its axis, means in said frame 120 below said printing means for forming successive matchstems by transversely slitting said strip from each edge to a predetermined distance from said axis, and means in said frame below said slitting means for alternately offsetting said matchstems on both sides of said stem.

14. In apparatus for the manufacture of matches from a continuous strip of cardboard, the combination of a vertical frame, 125

printing means in said frame adapted to engage a downwardly travelling strip of cardboard, means for transversely slitting the edge portions of said strip into two series 5 of matchstems extending outwardly from the central portion of said strip, means for alternately offsetting the matchstems on both sides of said strip, and guides adapted to engage between alternate matchstems on 10 both sides of said strip.

15. In apparatus for the manufacture of matches from a continuous strip of cardboard, the combination of means for continuously moving said strip, means for forming two 15 series of matchstems by transversely slitting both edge portions of said strip, means for separating each series of matchstems into two rows of matchstems by alternately offsetting said matchstems on both sides of said 20 strip, guides adapted to engage each between two rows of matchstems, said guides comprising a pair of laths of triangular cross-section, means for successively tipping the two rows of matchstems on each side of said strip, 25 said guides extending above said tipping means.

16. In apparatus for the manufacture of matches from a continuously moving strip of cardboard, the combination of means for 30 transversely slitting both edge portions of each strip to form two series of matchstems, means for separating each series of matchstems into two rows of alternated matchstems, guides adapted to engage each between two rows of matchstems, two tipping 35 devices arranged one behind the other, said guides being twisted to successively present one series of matchstems to the first tipping device and the other series of matchstems to 40 the second tipping device.

17. In apparatus for the manufacture of matches from a continuously moving strip of cardboard, the combination of means for transversely slitting both edge portions of 45 each strip to form two series of matchstems, means for separating each series of matchstems into two rows of alternated matchstems, guides adapted to engage each between two rows of matchstems, two tipping 50 devices arranged one behind the other, each tipping device comprising a tank for the tipping composition and a rotary disc partly immersed in said composition, said disc having two peripheral grooves adapted to engage 55 each the tips of a row of matchstems, said guides being twisted at various points to present the two rows of one series of matchstems to the first tipping device and then the two rows of the other series of matchstems 60 to the second tipping device.

18. In apparatus for the manufacture of matches from a continuously moving strip of cardboard, the combination of means for transversely slitting both edge portions of 65 each strip to form two series of matchstems,

means for separating each series of matchstems into two rows of alternated matchstems, guides adapted to engage each between two rows of matchstems, two tipping devices arranged one behind the other, said 70 guides being twisted to successively present one series of matchstems to the first tipping device and the other series of matchstems to the second tipping device, means for blowing hot air on said strip as it leaves each tipping 75 device, a closed chamber above said tipping devices, means for circulating said strip through a zigzag course in said chamber, and a rotary cutter for cutting said strip into leaves as it comes out of said chamber. 80

In testimony whereof I affix my signature.
